UNITED STATES PATENT OFFICE.

ANDERS WIKLUND, OF CHICAGO, ILLINOIS, ASSIGNOR TO INTERNATIONAL HARVESTER COMPANY, OF CHICAGO, ILLINOIS, A CORPORATION OF NEW JERSEY.

PITMAN.

Application filed March 1, 1922. Serial No. 540,179.

This invention relates to pitman connections for mowers and like machines.

In a pitman having one or more resilient jaws for clamping the bearing member of the mower knife head, it has been found that the grassward end of the pitman has, in some instances, become disengaged or separated from the knife head. This accidental separation of the grassward end of the pitman from the bearing member on the end of the knife head has occurred in some instances when the mower knife has encountered some tough or unyielding obstruction, such, for instance, as a stick or a stone. This obstruction in such instances prevents the reciprocation of the knife as the crank continues to revolve and the pitman is pulled away from the knife head, and the bearing is snapped from the clamping jaws. This invention has for one of its objects to remedy this condition by providing means utilized in connection with a pitman having one or more resilient jaws for preventing the accidental separation of the grassward end of the pitman from the bearing member of the mower knife head.

A further object is to provide a simple and economical construction or clamping device in which the movable parts are substantially confined within the pitman straps.

These and other objects are accomplished by providing a clamping jaw and means for actuating said clamping jaw, said actuating means having means for preventing the accidental spreading of the pitman straps or jaws when the same are in clamping position.

In the accompanying drawings I have illustrated but one embodiment of my invention, and in these drawings—

Figure 1 is a plan view of the grassward end of a pitman having my improvement embodied therein;

Fig. 2 is a side elevational view of Fig 1;

Fig. 3 is a sectional view taken on the lines 3—3 of Fig. 2 showing the pitman in its inoperative or disengaged position;

Fig. 4 is a detail view partly in section showing the position of the clamping member;

Figs. 5 and 6 are enlarged detail views of the toggle link members; and

Fig. 7 is a detail view of the connecting link between the clamping member and the crank.

The stubbleward end 10 of the body portion of the pitman preferably made of wood, is provided with, and has secured thereto by means of rivets 11', resilient jaws or straps 11 and 12, which in turn are provided with cup-shaped cavities or bearing portions 13 and 14 respectively which are adapted to receive the ball of the pitman head formed on the knife head of the mower. The resilient jaws are provided adjacent the cup-shaped portions with registering elongated apertures 15 arranged longitudinally with respect to the straps. The inner portions of these slotted apertures are provided with beveled surfaces 16 for the purposes hereinafter set forth. The bearing or cup-shaped portions 13 and 14 are provided with inclined outside surfaces 17, which are adapted to be slidably engaged by a clamping fork member 18 in a manner to force the straps 11 and 12 on the spherical bearing member of the knife head. The clamping member 18 is provided with outside inclined surfaces 19 adapted to engage the inclined surfaces 16 of the straps 11 and 12 in its normal operation of unclamping or spreading and releasing the jaws from the knife head. The stubbleward end of the clamping member 18 is provided with a bifurcated portion 20, which is adapted to pivotally receive a link 21. The free end of the link 21 is provided with a slotted opening 22, which slidably receives the pin 23 which in turn is fixed to the free end of arms 24 of a crank 25. It will be noted that the slot 22 is sufficiently long to permit free reciprocation of the link 21. The crank 25 is pivotally mounted in the straps 11 and 12 by the bearing studs 26 and 27 journaled in the enlarged portions 28 and 29 respectively of the straps 11 and 12. One end of the crank member 25 is provided with a protruding square shank or wrench engaging portion 30, which is adapted to be manipulated by a wrench or other tool in clamping and unclamping the jaws of the pitman from the knife head. Between the arms 24 of the crank 25 is a flattened shoulder portion 25' for the purpose hereinafter set forth. The toggle link 21 is provided with a resilient means comprising a spring 31 surrounding the link 21 and extending from the portion 20 of the clamping member 18 to a collar 32, which is slidably supported on the link 21. The collar 32 is 110

provided with a narrowed or reduced portion 33 adapted to fit between the arms 24 and engage the pin 23 in the normal operation of clamping the pitman.

5 It will be noted that the spring 31 normally forces the clamping member 18 grasswardly with respect to the pitman proper, and therefore holds the straps or jaws 11 and 12 under spring tension in clamping the 10 spherical bearing member of the knife head.

It will also be noted that when the clamping member 18 is in its clamping position or the position shown in Fig. 1 that this member 18 is limited in its movement stubwardly with respect to the pitman by reason of the slotted end of link member 21 butting against the flattened portion 25' of the crank 25. In other words, when the pitman is in the position shown in Fig. 1 the 20 straps 11 and 12 cannot become accidentally disengaged from the bearing member of the knife head by reason of the knife encountering some obstruction. It should be appreciated that when the parts are in clamping 25 position, the stubbleward end of the link 21 does not abut the flattened shoulder portion 25' on the crank, but rather is slightly spaced therefrom. Figure 2 clearly shows this. Should, however, an obstruction 30 be encountered by the cutting apparatus of the mower, or the like, then, by means of the sliding pivotal connection of the link with the crank, the link will move to abut the shoulder portion. Thus further movement of the link is prevented; the parts are 35 securely locked, and accidental unclamping of the pitman jaws is effectually prevented.

The strap member 12 is provided on its inner side with a projection 34 adapted to 40 engage or form a stop for the arm 24 of the crank member 25, as clearly shown in Fig. 1. When it is desired to release the bearing member of the knife head from the pitman or from the cup-shaped members 13 and 14 a wrench is applied to the square 45 shank 30, and the same is swung in a direction to release the crank 25 from the stop 34 to a position shown in Fig. 3, in which position the clamping member 18 is obviously withdrawn from the inclined surfaces 17 of the straps 11 and 12 until the inclined surfaces 19 of the clamping member 18 engages the inclined surfaces 16 of the straps 11 and 12, during which engagement 50 the straps 11 and 12 are positively spread and thereby releasing the bearing member of the knife head. When it is desired to clamp the bearing member to the pitman proper the reverse operation is performed.

60 From the above description it will be seen that I have provided a simple and easily operated construction for connecting the pitman to the knife head of a mower or the like in such a manner that the wear between 65 the co-operating parts will be automatically

taken up, and that the accidental separation of the co-operating parts will be prevented.

While I have in the above specification described one embodiment which my invention may assume, it will be understood 70 that the invention is capable of modification and that modification may be employed without departing from the spirit and scope of the invention as expressed in the following claims.

75 What I claim as new and desire to secure by Letters Patent is:

1. In a pitman connection, a pitman having resilient jaws, a jaw clamping member, a link connected to said clamping member, a crank pivoted to said pitman and connected to said link, and means causing relative longitudinal movement of said link and clamping member with respect to said crank after said clamping member is in clamping position, whereby one end of the link and a portion of the crank abut to lock the parts in such clamping position. 85

2. In a pitman connection, a pitman having resilient jaws, a clamping member pivoted to said jaws, and means including a slotted link connecting the member and jaws for preventing the accidental unclamping of said clamping member after said member is in clamping position. 90

3. In a pitman connection, a pitman having a resilient jaw, a movable member for clamping the jaw, a crank for actuating the movable member, a shoulder portion on the crank, one end of the movable member when in normal clamping position being spaced from said shoulder portion, and means causing said movable member and shoulder portion to abut to prevent accidental unclamping of the jaw. 100

105 4. In a pitman connection, a pitman having a resilient jaw, a longitudinally movable member for clamping the jaw, a crank for actuating the movable member, a shoulder portion on the crank, one end of the movable member when in normal clamping position being spaced from said shoulder portion, and means causing said movable member and shoulder portion to abut to prevent longitudinal movement of the movable member. 110

5. In a pitman connection, a pitman having resilient straps, a reciprocable member carried by the straps for clamping said straps, a crank journalled in the straps for reciprocating the member, a shoulder portion on the crank, one end of the reciprocable member when in normal clamping position being spaced from the shoulder portion, and means causing said reciprocable member and shoulder portion to abut to prevent accidental unclamping of the straps. 125

6. In a pitman connection, a pitman having resilient straps, clamping means for the straps including a link and a crank, the 130

crank having a shoulder portion, one end of the link lying spaced from the shoulder on the crank when the clamping means is in clamping position, and means causing the link to abut the shoulder to prevent accidental unclamping of the straps.

7. In a pitman connection, a pitman having resilient straps, clamping means for the straps including a link and a crank, the crank having a shoulder portion, one end of the link lying spaced from the shoulder on the crank when the clamping means is in clamping position, and a sliding pivotal connection between the link and crank causing the link to abut the shoulder to prevent accidental unclamping of the straps.

8. In a pitman connection, a pitman having resilient straps, clamping means for the straps including a movable slotted link, a two-armed crank journaled in the straps, a pin carried by the arms of the crank, the slotted end of the link being carried by the pin, and a shoulder portion between the two arms of the crank, the shoulder and end of the link being adapted to cooperate in clamping position of the parts to prevent accidental unclamping thereof.

9. In a pitman connection, a pitman having resilient straps, a clamping member for

the straps, a crank and a link for actuating the clamping member, the link being pivoted at one end to the clamping member, the crank being pivoted at one end to the straps, and a sliding pivotal connection between the other end of the crank and the other end of the link causing both longitudinal and lateral movement of the link, a shoulder on the crank to limit longitudinal movement of the link in clamping position of the parts, and other means for limiting the lateral movement of the crank and link in one direction.

10. In a pitman connection, a pitman having resilient straps, a clamping member including a crank and a link pivotally carried between said straps, said link having both lateral and longitudinal movement, means for limiting the longitudinal movement of said link for holding the clamping member in clamping position by causing the link to abut the crank, and stops formed on the straps for limiting the lateral throw of the clamping member in one direction by causing one of the said members comprising the clamping member to contact said stops.

In testimony whereof I affix my signature.

ANDERS WIKLUND.
